UNITED STATES PATENT OFFICE.

RICHARD M. CRAIG, OF SAN ANTONIO, TEXAS.

ADVERTISING-SIGN.

1,312,237.

Specification of Letters Patent. Patented Aug. 5, 1919.

Application filed August 21, 1917. Serial No. 187,413.

To all whom it may concern:

Be it known that I, RICHARD M. CRAIG, a citizen of the United States, residing at San Antonio, in the county of Bexar and State 5 of Texas, have invented certain new and useful Improvements in Advertising-Signs, of which the following is a specification.

This invention relates to advertising signs and more particularly to that class which 10 are displayed by illumination. While there are many signs of this type now in general use they do not attract as much attention as is desired nor as much attention as is warranted by the expense of their installation 15 and upkeep. Ordinarily these signs are stationary and are intermittently illuminated for the purpose of attracting attention thereto or in some instances the sign is painted or otherwise depicted upon a traveling band, 20 the motion of which also is intended to attract attention. With the object in view of providing a sign which will attract more attention than signs of the general type above mentioned and which will at the same time 25 be no more expensive than the ordinary signs both to install and maintain, the present invention aims to provide a sign which, in operation, will appear to be animated, will be displayed with colors and in addition to the feature of apparent animation, 30 will also travel during display so as to adapt it for the successive display of a number of different signs or the successive portions of a single sign.

35 More specifically, the invention aims to provide in an advertising sign, a traveling band bearing various advertising matter such, for example, as figures which will appear animated when the sign is in operation 40 or will apparently change their outline or position, letters or figures which will apparently shrink and expand, or apparently become alternately broad and narrow, etc., the band being illuminated during its travel 45 and the arrangement of the band and construction of the apparatus as a whole being designed to automatically accomplish the results stated.

Briefly stated, the band of the sign bears 50 advertising matter, such, for example, as letters or other symbols printed or otherwise depicted in superposed relation in different positions or different dimensions, figures of movable objects, of persons, or of animals, 55 etc., also printed or otherwise depicted in superposed relation in different positions, the

superposed or overlapping impressions being in different colors, such, for example, as red and green or red and bluish green and means being provided for illuminating the 60 display stretch of the band alternately with red and green or red and bluish green light, the green outlines of the sign being rendered visible alone when the red light is flashed and the red outlines alone being rendered visible when the green or bluish green 65 light is flashed.

The invention also aims to provide in a sign of the character generally described above, a display band of transparent or 70 semi-transparent material bearing the sign characters upon its reverse side so that its plain side will be exposed to view when the sign is not in operation thereby giving to the sign an air of mystery which enhances 75 its advertising value as when not in operation no indication is given as to the manner in which the results are produced when the sign is illuminated and in operation.

Another aim of the invention is to provide in connection with the lights for illuminating the sign, a flasher which is so constructed as to alternately supply current to the red and green lights and between the 80 periods of illumination be inactive for a 85 short period of time so as to increase the effect of animation due to persistence of vision during the period of comparative darkness or occultation.

In the accompanying drawings:

90 Figure 1 is a perspective view of the advertising sign embodying the present invention;

Fig. 2 is a horizontal sectional view therethrough;

Fig. 3 is a vertical front to rear sectional view on the line 3—3 of Fig. 2;

Fig. 4 is a perspective view of the rotary flasher for alternately closing the circuit through the red and green lights;

Fig. 5 is a perspective view of the display band removed from the casing of the sign;

Fig. 6 is a diagrammatic view illustrating the wiring for the lights, motor, and rotary 105 flasher.

The mechanism of the sign is mounted within a suitable casing which is here shown as rectangular and relatively long and shallow, although it will be understood that 110 the casing may assume various other shapes and relative dimensions and that it may be

of any desired size and constructed in any desired manner and of any suitable material. The casing is indicated in general by the numeral 1 and includes a top 2, bottom 3, 5 rear wall 4, and end walls 5, the casing being open at its front and having fitted in its open front a transparent pane 6 of glass or other material suitable for the purpose. It is preferable that the top 2 of the casing 10 be removable so that the display band may be readily removed when desired and another band carrying different advertising matter substituted therefor, and the said band is endless and is passed about rolls 15 which are arranged in a manner which will now be described. Two of the rolls, indicated by the numeral 7, are mounted within the casing at one end thereof for free rotation and a similar pair of rolls 8 is 20 mounted within the casing at the other end thereof. A drive roll 9 is mounted in suitable bearings near the first-mentioned end of the casing and is driven from an electric motor as will be presently described. The 25 display band, which is indicated by the numeral 10, is passed about the rolls 7, 8 and 9 in the manner clearly shown in Fig. 2 of the drawings, and also about another roll 11, which is mounted within the casing 30 at the last-mentioned end thereof and rearwardly of the rolls 8 and which is held under tension by means of a suitable spring or springs 12 so that the band 10 is at all times held taut and is caused to frictionally engage the roll 9 so as to be caused to travel when the last-mentioned roll is rotated. The electric motor above referred to is indicated by the numeral 13 and a belt 14 is driven from the shaft of this motor and 35 passes about a relatively large pulley 15. Rotatable with the pulley 15 is a smaller pulley 16 about which is passed a belt 17 trained also about a relatively large pulley 18 with which the roll 9 is connected for 40 rotation. It will be understood, of course, that the relatively rapid rotation of the shaft 13 is reduced by the gearing just described so that the band will be caused to travel at a relatively slow rate of speed behind the transparent pane 6, thus giving 45 full opportunity to read the successive portions of the sign or signs during the travel of the band and its illumination.

As before stated, the sign characters are 50 printed, painted, or otherwise depicted upon the reverse side or inner surface of the display band 10 and the outer face of the band is left plain. Also, as before stated, the band 10 is of semi-transparent or translucent material so that when illuminated from the rear the sign characters or symbols upon its inner face will be displayed to view as the display stretch passes the pane 6. These characters, when in the nature of letters or the like, are, of course, printed back-

ward upon the band so that they will read correctly as the display stretch of the band travels from right to left across the front of the casing. The arrangement of the advertising matter upon the band will be further specifically described in connection with the description of operation of the sign.

Mounted upon the base 3 of the casing are suitable supports 19 upon which are mounted electric lamp sockets 20 for the support of lamps 21 and 22 which may be arranged, as shown in Figs. 2 and 3 of the drawings, or in any other suitable manner. In any event certain of the lamps, as, for example, the 75 lamps 21, are red and the lamps 22 are bluish green in color, and current is supplied to these lamps through a suitable conductor cord 23 carrying a plug 24 for connection with the usual electric lamp socket, 80 the supply of current being controlled by a rotary flasher which will now be described. The flasher preferably comprises a cylindrical body 25 of fiber or any other suitable non-conducting material mounted for rotation upon a suitable spindle 26 upon the bottom 3 of the casing. A belt 27 is passed about the lower end of the body 25 and about a pulley 28 associated with the pulley 18 and in this manner rotary motion is imparted to 85 the flasher from the motor 13. A continuous contact strip 29 is mounted upon the body 25 and completely circumscribes the same and other contact strips 30 and 31 are mounted upon the body at diametrically opposite 90 sides thereof and respectively above and below the strip 29 and each of these strips 30 and 31 extends slightly less than one-half way around the body and the strips are so relatively arranged that the ends of one strip 100 terminate short of a vertical line passing through the ends of the other strip. In other words, there is a slight gap between the ends of the two strips which, as will be presently made clear, provides for a period of occultation in the operation of the sign. Contact fingers 32, 33 and 34, respectively engage the contact strips 29, 30 and 31 and the strips 30 and 31 are respectively electrically connected, as at 35 and 36, with the contact strip 29. 105 In Fig. 6 which illustrates diagrammatically the wiring for the sign it will be observed that one of the conductor wires is connected to the contact finger 32 and is therefore constantly in circuit with the strip 29. A wire 110 37 leads from the contact finger 33 and is in circuit with, for example, the red lamps 21 and a wire 38 leads from the contact fingers 34 and is in circuit with the bluish green lamps 22. The other conductor wire has 115 branches leading one to the red lamps and the other to the green lamps and the said conductor wires are further in circuit with the motor 13. At this point will be understood that when the sign is in operation, the 120 125 130

motor 13 will be rotated causing the band to travel and also imparting rotary motion to the flasher 35. As the flasher rotates and as the display stretch of the band passes in front of the electric lamps, the circuit will be alternately closed through the contact strips 30 and 31 to alternately flash the red and bluish green lamps. It will be understood that the periods of illuminations of the display band are interrupted by periods of occultation due to the gap between the ends of the contact strips 30 and 31 and therefore due to persistence of vision, the eye will retain what is displayed by flashing of the red lamps, for example, during said period of occultation, and until the bluish green lamps are flashed.

Referring to Fig. 5 of the drawings it will be observed that the words of the advertising matter have respective letters printed or otherwise depicted in overlapped relation and that in the specific instance illustrated, certain of the letters are printed in red, as indicated by the numeral 39, and the corresponding letters in green or bluish green, as indicated by the numeral 40, these letters being arranged in overlapped or superposed relation and the letters 39, for example, being much shorter and broader than the letters 40. Also in the specific instance illustrated, there is shown the representation of a dancing figure which in one position is painted or otherwise depicted in red, as indicated by the numeral 41, and in the other position is depicted in bluish green, as indicated by the numeral 42. In like manner, for example, a semaphore signal may be shown in one position in bluish green and in another position in red as may also a rocking chair or, in fact, any other movable object, animal or the like. It will be understood from the foregoing description of the invention that as the display stretch of the display band passes the front of the casing, the red and bluish green lights will be automatically alternately flashed to illuminate the said stretch of the band so that in the instance of the letters 39 and 40, the letters 39 which are relatively short and broad will appear when the bluish green lights are flashed and the letters 40 will at such times be invisible. On the other hand, when the bluish green lights are flashed, the letters 40 which are relatively narrow and tall will appear and due to persistence of vision the effect will be that of alternate expansion and contraction of the letters. Due to the provision of means for providing for a period of occultation between the periods of illumination, this change in size and shape of letters will appear more gradual and, in fact, the letters will seem to actually expand and contract. In like manner in the instance of the figure which is printed in different colors, as indicated by the numerals 41 and 42, when

the bluish green lamps are flashed the image in its position as printed in red will appear and when the red lamps are flashed this position of the image will disappear and the image in the position printed in green will appear. As a result the image will appear as if animated and, of course, this condition will hold true in the movements of animals or objects having moving parts, such, for example as a railway semaphore, a rocking chair, or the like.

From the foregoing description of the invention, it will be further understood that in the operation of the sign there are three separate and distinct things which take place to produce the effect of animation or motion, namely, first, the travel of the display band across the open front of the casing, second, the change from one position to another of the moving parts of an object, and, third, the intermittent flashing of the lights.

Having thus described the invention, what is claimed as new is:

1. A device of the class described including a surface bearing in different colors and in superposed relation different positions or shapes of the same symbol, object, or the like to be displayed, and means for displaying said surface in the presence of a light medium capable of absorbing one of said colors and then displaying said surface in the presence of a light medium capable of absorbing another one of said colors.

2. A device of the class described including a surface bearing in different colors and in superposed relation different positions or shapes of the same symbol, object or the like to be displayed, and automatic means for displaying said surface in the presence of a light medium capable of absorbing one of said colors, occulting the said surface, and then displaying the said surface in the presence of a light medium capable of absorbing another one of said colors.

3. In a device of the class described, a display surface, means for imparting travel to said surface, the surface bearing in different colors and in superposed relation different positions or shapes of symbols, objects, or the like to be displayed, and means for displaying said surface in the presence of a light medium capable of absorbing one of said colors and then displaying said surface in the presence of a light medium capable of absorbing another one of said colors.

4. In a device of the class described, a display band, means for imparting motion thereto, means inclosing the said band and arranged to display the outer surface of a stretch of the band, the band being of translucent material and bearing upon its inner surface in different colors and in superposed relation, different positions or shapes of symbols, objects, or the like to be displayed, and means in rear of the display stretch of

the band for displaying said stretch in the presence of a light medium capable of absorbing one of said colors and then displaying said stretch of the band in the presence of a light medium capable of absorbing the other one of said colors.

5. In a device of the class described, a display band, means for imparting motion thereto, means inclosing the said band and arranged to display the outer surface of a stretch of the band, the band being of translucent material and bearing upon its inner surface in different colors and in superposed

relation, different positions or shapes of symbols, objects, or the like to be displayed, 15 and means in rear of the display stretch of the band for displaying said stretch in the presence of a light medium capable of absorbing one of said colors, occulting the said stretch, and then displaying said stretch of 20 the band in the presence of a light medium capable of absorbing another one of said colors.

In testimony whereof I affix my signature.

RICHARD M. CRAIG. [L.S.]
